UNITED STATES PATENT OFFICE.

FREDERICK A. BALLOU, JR., OF PROVIDENCE, RHODE ISLAND, ASSIGNOR TO B. A. BALLOU & CO. INC., OF PROVIDENCE, RHODE ISLAND, A CORPORATION OF RHODE ISLAND.

METHOD OF MAKING SWIVEL-RINGS.

1,262,735.

Specification of Letters Patent. Patented Apr. 16, 1918.

Application filed April 30, 1917. Serial No. 165,365.

To all whom it may concern:

Be it known that I, FREDERICK A. BALLOU, Jr., a citizen of the United States, and resident of the city of Providence, in the county 5 of Providence and State of Rhode Island, have invented certain new and useful Improvements in Methods of Making Swivel-Rings, of which the following is a specification.

10 This invention relates to a method of making swivel rings more particularly adapted to be employed on swivel catch devices for chains for personal wear, and the object of this invention is to provide 15 such a method whereby the swivel ring may be constructed entirely of one piece of metal and without the use of solder.

The invention further consists in a new and improved method of constructing this 20 ring which consists primarily in reducing a length of wire at intervals to form relatively large spaced-apart head portions thereon, piercing said head portions and then severing said length at one side of 25 each head-forming member, each having a reduced elongated body and head and subsequently bending the reduced elongated portion into substantially a ring form.

In the accompanying drawings:

30 Figure 1— is a side elevation partly in section showing the swivel ring as attached to a trunnion member.

Fig. 2— represents a portion of length of wire from which a plurality of these 35 swivel rings are formed.

Fig. 3— illustrates the first operation which reduces the wire at intervals leaving enlarged spaced-apart head portions.

Fig. 4— shows the head portions as reduced to a thickness equal to the diameter of the reduced or body portions.

Fig. 5— shows the head portions as pierced.

Fig. 6— shows one of the members as 45 severed from the length of wire.

Fig. 7— shows the body portion as having been bent in ring form and as abutting the opposite side of the head.

Fig. 8— is an end view of the head of 50 the device illustrating that portion from which the next adjacent member was severed.

The usual method of forming swivel rings of this character by soldering one end

of the wire onto the side of the head portion, which has a number of disadvantages; first, soldering heat discolors the metal; second, the soldering heat anneals or softens the metal; and third, a soldered ring of this character is not so strong and will not 60 withstand the strains or last as long as when formed without having been subjected to this soldering heat.

To obviate these objections, I have provided a new and improved method of forming a multiplicity of these devices all on a length of wire, in which I employ wire 10 of a diameter substantially that of the head portion of the device and then reduce this wire by swaging the same at intervals as at 70 11 leaving enlarged spaced-apart head portions as at 12.

These head portions as shown in Fig. 3 are left thicker, and formed in substantially spherical shape which thickness may then 75 be reduced if desired to substantially that of the reduced diameter of the wire as illustrated in Fig. 4. These head portions are then pierced as at 13, see Fig. 5, each for the reception of a trunnion portion 14 of 80 the hook or catch, see Fig. 1, on which it turns. These reduced portions are then cut at the point 15, illustrated in Fig. 5 by dotted lines, on one side of the head member. The reduced body portion is then bent 85 around as at 16 into substantially a ring form, its end 17 abutting the back or opposite side of its head portion, thereby causing the two severed sections to abut and cover each other.

90 This improved construction of swivel ring has a number of advantages over the old construction, among others being; first, by forming a multiplicity of these devices on a length of wire, a number may be operated upon at each swaging action, and the whole can be handled to much greater advantage than when made up in single pieces, thus greatly facilitating the manufacture, and so reducing the cost of construction to 100 the minimum; second, the drawing-out or swaging operation serves to harden the wire rendering it tough and strong and capable of resisting the maximum amount of strain it is called upon to withstand; third, this 105 operation serves to toughen and harden the swivel ring greatly increasing its wearing qualities.

Another feature of importance is that when these rings are made of rolled plate, the precious metal on the outside is not disturbed, and the base metal at the points 5 of severing will be covered by abutting the severed end 17 of the body portion against the severed portion 15, on the side of the head, thus effectually preventing exposure of any of the base metal.

10 Most of the above-mentioned advantages are not obtainable when the ring portion is soldered to the head portion of swivel rings.

Having thus described one illustrative embodiment of my invention and the best 15 mode known to me for carrying out my method, I desire it to be understood that although specific terms are employed, they are used in a generic and descriptive sense and not for the purpose of limitation, the 20 scope of the invention being limited only by the terms of the appended claims.

I claim:

1. An improved method of making swivel rings which consists in reducing a length of wire at intervals leaving head portions 25 spaced apart thereon, piercing these head portions, severing the lengths, and bending the reduced portion into ring form.

2. An improved method of making swivel rings, consisting in reducing a length of 30 wire at intervals and so forming relatively large spaced-apart head portions thereon, piercing said head portions, severing each length at one side of the head, and bending the reduced portion so that its severed end 35 abuts the point of severing on its head.

In testimony whereof I affix my signature in presence of a witness.

FREDERICK A. BALLOU, JR.

Witness:

HOWARD E. BARLOW.
